CLAIM

The ornamental design for a modular golf training mat system with replaceable surfaces as shown and described.

DESCRIPTION

FIG. 1 is a perspective view of the modular golf training mat system with replaceable surfaces;

FIG. 2 is a bottom perspective view thereof;

FIG. 3 is a top view thereof;

FIG. 4 is a bottom view thereof;

FIG. 5 is a front view thereof;

FIG. 6 is a side view thereof;

FIG. 7 is a perspective view showing the modular golf training mat system with replaceable surfaces in use; and,

FIG. 8 is an exploded perspective view showing the modular golf training mat system with replaceable surfaces in use. The broken lines shown in the drawings represent portions of the modular golf training mat system with replaceable surfaces and form no part of the claimed design.

1 Claim, 8 Drawing Sheets
